(57) **CLAIM**

The ornamental design for a bottle with straw lid, as shown and described.

DESCRIPTION

FIG. 1 is a top perspective view of a first embodiment of a bottle with straw lid, showing a drinking portion of the bottle with straw lid in a closed position.

FIG. 2 is a bottom perspective view of FIG. 1.

FIG. 3 is a left side elevation view of FIG. 1.

FIG. 4 is a right side elevation view of FIG. 1.

FIG. 5 is a front elevation view of FIG. 1.

FIG. 6 is a rear elevation view of FIG. 1.

FIG. 7 is a top view of FIG. 1.

FIG. 8 is a bottom view of FIG. 1.

FIG. 9 is a top perspective view of FIG. 1, showing a drinking portion of the bottle with straw lid in an open position.

FIG. 10 is a bottom perspective view of FIG. 1, showing a drinking portion of the bottle with straw lid in an open position.

FIG. 11 is a left side elevation view of FIG. 1, showing a drinking portion of the bottle with straw lid in an open position.

FIG. 12 is a right side elevation view of FIG. 1, showing a drinking portion of the bottle with straw lid in an open position.

FIG. 13 is a front elevation view of FIG. 1, showing a drinking portion of the bottle with straw lid in an open position.

FIG. 14 is a rear elevation view of FIG. 1, showing a drinking portion of the bottle with straw lid in an open position.

FIG. 15 is a top view of FIG. 1, showing a drinking portion of the bottle with straw lid in an open position.

FIG. 16 is a bottom view of FIG. 1, showing a drinking portion of the bottle with straw lid in an open position.

FIG. 17 is a top perspective view of a second embodiment of a bottle with straw lid, showing a drinking portion of the bottle with straw lid in a closed position.

(Continued)

FIG. 18 is a top perspective view of a second embodiment of a bottle with straw lid, showing a drinking portion of the bottle with straw lid in an open position.

FIG. 19 is a top perspective view of a third embodiment of a bottle with straw lid, showing a drinking portion of the bottle with straw lid in a closed position.

FIG. 20 is a top perspective view of a third embodiment of a bottle with straw lid, showing a drinking portion of the bottle with straw lid in an open position.

FIG. 21 is a top perspective view of a fourth embodiment of a bottle with straw lid, showing a drinking portion of the bottle with straw lid in a closed position; and,

FIG. 22 is a top perspective view of a fourth embodiment of a bottle with straw lid, showing a drinking portion of the bottle with straw lid in an open position.

The portions of the bottle with straw lid shown in broken line form no part of the claimed design.
